CLAIM

The ornamental design for a pair of doors for a portable dialysis cabinet, as shown and described.

DESCRIPTION

FIG. 1 is a perspective view of doors for a portable dialysis cabinet according to one embodiment;

FIG. 2 is a front view of the doors of the portable dialysis cabinet referenced in FIG. 1;

FIG. 3 is a rear view of the doors of the portable dialysis cabinet referenced in FIG. 1;

FIG. 4 is a left side view of the doors of the portable dialysis cabinet referenced in FIG. 1;

FIG. 5 is a right side view of the doors of the portable dialysis cabinet referenced in FIG. 1;

FIG. 6 is a top view of the doors of the portable dialysis cabinet referenced in FIG. 1;

FIG. 7 is a bottom view of the doors of the portable dialysis cabinet referenced in FIG. 1;

FIG. 8 is a top view of a pair of doors of a portable dialysis cabinet shown with environmental structure removed for clarity of disclosure; and,

FIG. 9 is a bottom view of the doors of the portable dialysis cabinet referenced in FIG. 8.

In the drawings, the broken lines depict environmental subject matter only and form no part of the claimed design.
